CLAIM

The ornamental design for a toy bugle, as shown and described.

DESCRIPTION

FIG. 1 is a front elevational view of a toy bugle showing of my new design and is also a mirror image of rear elevational view thereof;

FIG. 2 is a left side elevational view thereof;

FIG. 3 is a right side elevational view thereof;

FIG. 4 is a top plan view thereof;

FIG. 5 is a bottom plan view thereof; and,

FIG. 6 is a sectional view taken in the direction of the arrows on line VI—VI of FIG. 2.
